FLAME HARDENING TORCH

George L. Walker, Jersey City, N. J., assignor to
Air Reduction Company, Incorporated, New
York, N. Y., a corporation of New York

Application January 14, 1937, Serial No. 120,484

7 Claims. (Cl. 266—4)

This invention relates to equipment for hardening metal parts and has particular reference to oxy-fuel gas torches employed for that purpose.

The rapid heating which can be obtained with the high-temperature flames of oxy-fuel gas torches, especially those using acetylene as the fuel gas, and the convenience with which such heating can be localized, makes such a torch an advantageous source of heating for certain hardening operations.

It is an object of this invention to provide an improved torch which not only supplies the heat to the part, or local region to be hardened, but also applies a stream of quenching medium to the heated metal and in a definite relation with the heating jets to obtain the desired hardening and to effect uniform hardening.

In accordance with one feature of the invention, the relation of the heating and quenching jets can be changed to regulate the severity of the quench according to the kind of material and the use for which it is intended.

Another object of the invention is to provide improved apparatus for hardening both sides of a gear tooth simultaneously. The apparatus is suitable for similar hardening operations on both sides of ridges or parts other than gear teeth having their opposite faces either parallel or extending in angular relation to one another. The invention includes a tip supporting yoke affording substantially universal adjustment for positioning the tips with respect to the surfaces to be hardened.

Other features of the invention relate to the construction of the yoke, torch, and associated parts through which oxygen, fuel gas, and water or other cooling and quenching medium are conducted to the tip.

Other objects, features and advantages of the invention will appear or be pointed out as the specification proceeds.

In the accompanying drawings, forming part hereof:

Fig. 1 is a side elevation of flame hardening equipment embodying the invention, the tips being shown widely separated in full lines and in adjusted positions, for heating a gear tooth, in dotted lines;

Fig. 2 is an enlarged view, partly in section, of the valve end of the torch body shown in Fig. 1;

Fig. 3 is a view, partly in section, taken at right angles to Fig. 2;

Fig. 4 is an enlarged sectional view taken on the line 4—4 of Fig. 1;

Fig. 5 is an enlarged sectional view of the mixer, extension tube, and yoke connection of Fig. 1;

Fig. 6 is a sectional view on the line 6—6 of Fig. 5;

Fig. 7 is an enlarged view, mostly in section, showing the yoke and tip structure of Fig. 1, the section being taken through the quenching tip of the left-hand tip structure and through the heating tip of the right-hand tip structure;

Fig. 8 is a view looking in the direction of the arrows 8—8 of Fig. 7 but showing part of the structure in section;

Fig. 9 is a top view taken on the line 9—9 of Fig. 7 but with the yoke arms turned into different positions to bring the tips closer together than in Fig. 7; and

Fig. 10 is an enlarged sectional view on the line 10—10 of Fig. 7.

The flame hardening torch shown in Fig. 1 includes a body portion 11, mixer 12, extension tube 13, elbow 14, yoke 15, and two tip structures 16 and 17, one on each branch of the yoke. The elbow 14 is replaced with a straight connector when it is more advantageous to have the body portion, mixer, and extension tube in line with the tip or tips instead of at right angles as in Fig. 1. The yoke 15 can be dispensed with when only one tip structure is used. The yoke illustrated provides substantially universal adjustment of the tips. If the torch is to be used with two tips but with no adjustment, or only simple adjustment of the spacing, a yoke structure having fewer joints can be used in place of the universal yoke 15.

At one end of the torch body 11 there is a valve block 20 with inlet connections 21, 22 and 23 for joining the torch to supply lines for oxygen, fuel gas, and a quenching fluid. The fuel gas used is preferably acetylene. Water is a satisfactory and inexpensive quenching fluid, though other liquids or gas are suitable. The preferred embodiment of the invention will be described with acetylene and water used as the fuel gas and quenching medium, respectively.

The oxygen inlet connection 21 communicates with a passage 25 leading through the body portion of the torch. The inlet connection joins an acetylene passage 26 leading through the body portion 11. Both the oxygen and acetylene passages 25, 26 are commanded by the same valve in the torch illustrated. This valve 28 is shown in open position in Fig. 2.

Water from the inlet connection 23 flows through a passage 30 (Fig. 3) and there is a turn cock 31 in the valve block for shutting off the water flow.

Beyond the valve block 20, the body portion 11 comprises a sleeve 33 in which the passages 25, 26, and 30 extend through pipes as shown in Fig. 4. The mixer end of the body portion of the torch is shown in Fig. 5 with the mixer 12 held in position by a nut 35.

The acetylene passage 26 communicates with the end of a mixing bore 37 through the center of the mixer. The oxygen passage 25 terminates in an annular chamber 38 from which the gas flows through angularly disposed orifices into the mixing bore 37. The water passage 30 ends in an annular space 39 and the mixer has a plurality of water passages 41 disposed in a circle around the mixing bore and opening into the annular space 39 at one end and another annular space 42 at the discharge end of the mixer.

The extension tube 13 comprises an outer tube 44 and an inner tube 45, each soldered to an adapter 46 at one end and to the elbow 14 at the other end. The adapter is fastened against the discharge end of the mixer 12 by a connector nut 47. A center opening through the adapter 46 permits mixed gases from the bore 37 to flow into the inner tube 45, while a plurality of other openings through the adapter permit water from the annular space 42 to flow into the chamber between the outer tube 44 and inner tube 45.

The oxygen and acetylene become thoroughly mixed during their passage through the extension tube. The conduit through which these gases pass is entirely surrounded by cooling water. The mixed gases flow through a central opening in the elbow 14, and the water flows through a ring of passages surrounding the central opening and terminating in an annular space 49. A gland 50 is soldered into the discharge end of the elbow 14 and has passages communicating with the passages through the elbow, the water passages terminating, as in the other parts, in an annular space 52.

Fig. 7 shows the construction of the yoke 15. A yoke member 54 has its stem portion held against the gland 50 by a nut 55 which clamps against a collar 56 on the gland. There is a central gas passage 57 and side water passages 58 through the stem portion of the yoke, the relation of these passages being best shown in Fig. 9. Similar gas and water passages in the vertically extending branches of the yoke member 54 are connected with the passages of the stem portion through horizontal conduits 60 and 61 (Figs. 7 and 8) which are formed by drilling through the yoke member and then closing the ends by plugs 62.

An adjusting arm 63 is supported from each branch of the yoke member 54. Each adjusting arm 63 has a gland 64 soldered to its upper end, and the gland is held against the lower face of one branch of the yoke member 54 by a nut 65. The gland 64 has a circle of water passages with annular spaces at both ends of these passages so that it is not necessary for the water passages in the gland to register with the water passages in the connected parts. The arm 63 can be swung about the axis of the central gas passage through gland 64 and adjoining yoke branch to effect one of the adjustments of the tip.

The outer end of the adjusting arm 63 has downwardly extending passages near its outer end and a gland 67 soldered to it below these passages, the construction being similar to the upwardly extending gland 64. Horizontal drillings in the arm 63, similar to the passages 60 and 61 in the yoke member 54, provide separate

gas and water passages similar to those in the yoke member 54.

A tip arm 69 is held against the end of the gland 67 by a nut 70 which screws on threads on the upper portion of the tip arm 69. There is a central gas passage through the gland 67 and a passage 71 through the tip arm in alignment with the center passage of the gland 67. The tip arm 69 can be rotated about the axis of these central gas passages to effect another adjustment of the tip. There is a water passage 73 on each side of the gas passage 71.

The tip structure 16 includes a head portion comprising a block 74 with a seat which fits a conical end 75 of the tip arm 69. The block 74 is held on the tip arm by a nut 76 and can be rotated about the axis of the conical end 75 to adjust the slope of the tip structure.

There are two annular recesses 78 and 79 in the conical end 75 of the tip arm. The recess 78 connects with the center passage 71 through radial ports and an axial passage 81. The annular recess 79 communicates with the water passages 73 through angular ports 82.

The tip structure includes also two tips 84 and 85 supported by the block 74. The tip 84 fits into a recess in the bottom face of the block, as shown in Fig. 7, and is held in place by a bushing 86 which surrounds the tip 84 and threads into the recess far enough to bear against a collar at the upper end of the tip. Water discharges from a conduit 87 in the tip 84 through orifices 88. The conduit 87 communicates with the recess 79 (Fig. 8) through passages 90 (Fig. 7) in the block 74.

There is no sectional view of the tip 85 but the construction is the same as that of the corresponding tip 85' of the tip structure 17. Parts of the two tip structures are designated by the same reference characters with a prime appended to the parts of the tip structure 17.

The tip 85' fits into a conical tip seat in the block 74'. A bushing 92' similar to the bushing 86 bears against a shoulder of the tip 85' to hold the tip in place. Gas from the annular recess 78' flows through a passage 93' to a central conduit 94' in the tip 85'. The gas discharges from the conduit 94' through jet orifices 95' and the gas jets from these orifices are ignited and comprise the flames for heating the part to be hardened.

The tip 85' is cooled by water flowing through passages 96' which open into an annular recess 97' near the upper end of the tip 85'. Water is supplied to this recess 97' through a water passage 98' (Fig. 10) which is a branch conduit from the passage supplying water to the quenching tip 84'. The cooling passages 96' terminate in a chamber 99' in the tip and water flows from that chamber through cooling-water discharge passages 100'.

Fig. 9 shows the adjusting arms 63 and 63' rotated into nearly parallel positions in order to bring the tip structures 16 and 17 closer together. The tip arms are turned about the axis of the passage 71 to counteract the turning movement of the adjusting arms 63. The desired angular relation of the heating and quenching jets is obtained by swinging the tip structure 16 and 17 about the axes of the conical ends 75 and 75' of the tip arms.

Figs. 1 and 8 show the outline of a portion of a gear 102 in dotted lines. In the operation of the torch the tip structures are adjusted to the desired spacing from the opposite faces of

the gear tooth or other part to be hardened. The torch is then traversed, with respect to the surfaces to be heated, in the direction indicated by the arrow in Fig. 8. The flames from the 5 heating tip 85 heat the surface progressively from right to left. The heating time is determined by the speed of the relative movement of the torch and work.

The quenching tip 84 moves progressively 10 across the surface a short distance behind the heating tip 85. The construction by which the tips 84 and 85 are attached to the block 74 makes it possible to rotate these tips at their connections to the block 74 so that the flame jets and 15 water jets can be directed against the work in planes parallel to each other, or in converging or diverging planes. When one or both tips are rotated to cause the flame jets and water jets to lie in converging planes then the quenching 20 occurs a shorter distance behind the heating than with the heating and quenching jets directed in parallel planes. The time of quenching can be delayed by turning the tips to direct the jets in diverging planes. By means of these 25 tip adjustments the severity of the quench can be regulated according to the kind of steel and the use for which it is intended. The bushings 86 and 92 can be screwed up until they provide enough friction to prevent displacement of the tips from any set positions.

If both of the tips 84 and 85 are made integral with the block 74 the space between the points at which the flame and water jets strike the work can not be adjusted, but a limited range of adjustment can be obtained if either one of these tips is integral with the block but the other rotatable. Although both tips 84, 85 are adjustable in the illustrative embodiment of the invention, they are attached to the block 74 in such a manner that they form with that block a unitary tip structure.

Changes and modifications can be made in the embodiment which has been illustrated and described, and some features of the invention 5 can be used without others.

What is claimed as new is:

1. In a flame hardening torch, a tip structure having two perforate faces and conduits through which fuel gas is delivered to the perforations 50 of one face and a quenching medium delivered to the perforations of the other face so that flame jets and quenching jets are projected from said faces against the surface of the part to be hardened, at least one of said faces being 55 on a portion of the tip structure which is movable with respect to the other face to change the relation of the perforations in the respective faces and regulate the distance between the regions where the heating jets and the quenching 60 jets strike the surface of the part to be hardened.

2. In a flame hardening torch, a tip structure comprising a head portion, a perforated face portion connected with the head portion, a conduit through which quenching fluid is supplied 65 to said perforated face portion for discharge through the perforated face against the work which has been heated by the torch, and a tip held in the head portion and having one or more jet orifices for projecting heating flames

against the work, said tip being movable about its connection to the head portion to cause the heating jets to strike the work at various distances ahead of the quenching medium.

3. In a unitary tip structure for a flame hardening torch, a head portion and two separate tip portions comprising elongated hollow members and each having a plurality of jet orifices opening through one side and extending transversely of the long dimension of the hollow 10 member, a conduit in said head portion through which heating gas is supplied to the hollow interior of one of said hollow members, another conduit in said head portion through which quenching fluid is supplied to the interior of the 15 other hollow member, for projecting quenching jets against the work, a cooling member in the wall of the hollow member that produces the heating flames, and a branch conduit in said head portion through which some of the quench- 20 ing fluid is diverted into said cooling chamber.

4. Flame hardening equipment including a torch body, a tip structure, and a swivel joint in the connection of the tip structure to the torch body, jet orifices in the tip structure some 25 of which project flames against the work and others of which project quenching fluid streams against the work behind the flames, separate passages through the torch body for fuel gas and quenching medium, and similar passages 30 in the tip structure communicating with those in the torch body through the swivel joint.

5. A heating torch including a body, a tip structure, and connections between the tip structure and torch body including two or more swivel joints with their axes in such relation that the tip structure has universal movement with respect to the torch body, and two or more conduits leading through the torch body and tip structure and all connecting through each of 40 said swivel joints.

6. A flame hardening torch including a body portion, two separate branches extending generally downward from the body portion, two swivel joints in each of said branches movable 45 about substantially vertical axes, the portion of the branch between the swivel joints extending transversely of the axes of the joints, a downwardly extending portion on each branch below the second swivel joint, and a torch tip connected with each branch at the lower end of said downwardly extending portion, said tips having confronting faces with jet orifices for directing heating flames against opposite sides of a part to be hardened, and being adjustable toward and from one another by the combined swivel movement of said joints.

7. A flame hardening torch including a body portion and a yoke extending from the body portion with heating and quenching torch tips on the ends of the branches of the yoke, conduits in the branches for supplying fuel gas and quenching fluid to the torch tips, and one or more swivel joints in each branch for effecting adjustment of the spacing of the torch tips from each other, the fuel gas and quenching fluid conduits extending through said swivel joints.

GEORGE L. WALKER.
